UNITED STATES PATENT OFFICE.

ALFRED C. MOORK, OF CHICAGO, ILLINOIS.

GAS-BURNER.

1,380,004.

Specification of Letters Patent. Patented May 31, 1921.

Application filed August 26, 1920. Serial No. 406,058.

To all whom it may concern:

Be it known that I, ALFRED C. MOORK, a citizen of the United States of America, and a resident of Chicago, county of Cook, and 5 State of Illinois, have invented certain new and useful Improvements in Gas-Burners, of which the following is a specification.

The purpose of this invention is to provide for efficient combustion by effecting an 10 extremely intimate mixture of the incoming gas and air by a substantially two-part burner formed of a pair of simple castings.

The objects of the invention are accom- 15 plished by the device shown in the accompanying drawings, in which—

Figure 1 is a transverse vertical section of a gas burner constructed according to this invention.

20 Fig. 2 is a bottom plan view of the cover portion of the burner.

Fig. 3 is a plan view of the base of the burner.

The invention as embodied in the drawings 25 comprises a base portion and an inter-fitting hollow cover, said cover having a depending serrated conical spreader opposite the central air and fuel inlet in the base. Both the cover and the base are provided 30 with overlapping inwardly projecting flanges which are toothed or serrated, the serrations being in staggered relation, and also being staggered with respect to the serrations on the conical spreader. By this ar- 35 rangement the incoming gas and air is first projected against the central spreader on the cover and divided into a plurality of streams which strike against the toothed portion of the flange on the base, thus being broken 40 up and caused to eddy around through the interdentals in the flange and then, by striking the flange on the cover, being further broken up before passing through the open- 45 ings in the latter flange and toward the burner outlets in the cover.

Referring to the drawings, the base 1 is in threaded engagement with the supporting nipple 2 having the usual air and gas inlets of the Bunsen burner. The cover 50 portion 2 is a hollow cylindrical member the side walls 3 of which rest on the base 1 outside of a small annular centering flange 4. Parts 1 and 2 of the burner are secured together by a pair of bolts 5. The top 6 55 of the cover 2 has a central depending serrated conical spreader 7 opposite the outlet

of nipple 2. The teeth 8 of the spreader 7 are in staggered relation with upstanding teeth 9 of the annular flange 10 surrounding the cone 7 and integral with the base 1. 60 The cover 2 is provided with a depending annular flange 11 surrounding the flange 10 and having apertures 12 therein opposite the teeth 9 of flange 10. The space 13 between the flange 11 and the side wall 3 of the cover 65 provides for a further mixture of the gas and air as the currents eddy in this space before leaving the burner through the burner outlets 14.

In the operation of the device the air and 70 gas entering it through the nipple 2 is first divided into a plurality of streams by encountering the conical spreader 7. This spreader serves to direct more or less the divided streams against teeth 9 of the flange 75 10, the gas and air being mixed upon re-bounding and circulating through the spaces between the teeth, and is further mixed by again striking the flange 11 before passing through the apertures 12 into the chamber 80 13. By the arrangement described a sub-stantial two-part burner formed of a pair of simple castings is made highly effective 85 for the purpose of insuring good combustion by effecting a finely divided mixture of gas and air.

Although but one specific embodiment of 90 this invention has been herein shown and described, it will be understood that numerous details of the construction shown may be altered or omitted without departing from the spirit of this invention as defined by the following claims.

I claim:

1. A gas burner having a base portion and 95 a cover portion, the base portion being provided with an inlet for gas and air and the cover portion being provided with a spreader cone projecting toward said inlet, said cone having grooves formed therein and radiating 100 from the apex.

2. A gas burner comprising, a base hav- 105 ing an inlet for gas and air and a serrated flange surrounding said inlet, a cover having a depending serrated flange outside of the serrated flange on the base, the serrations of the two flanges being in staggered relation.

3. A gas burner comprising, a base hav- 110 ing an inlet for gas and air and a serrated flange surrounding said inlet, a cover hav-ing a depending serrated flange outside of

the serrated flange on the base, the serrations of the two flanges being in staggered relation, and a central depending serrated spreader cone on said cover opposite said 5 inlet.

4. A gas burner comprising a base having an inlet for gas and air and a serrated flange surrounding said inlet, the cover having a depending serrated flange outside of the ser-

rated flange on the base, the serrations of 10 the two flanges being in staggered relation, and a central depending serrated cone on said cover opposite said inlet, the serrations on said cone being in staggered relation with the serrations on the flange of the base. 15

Signed at Chicago this 20th day of August, 1920.

ALFRED C. MOORK.
